(57) CLAIM

The ornamental design for a button cover with a clasp, as shown and described.

DESCRIPTION

FIG. 1 is a bottom perspective view of a button cover with a clasp.

FIG. 2 is a bottom view of a button cover with a clasp.

FIG. 3 is a top view of a button cover with a clasp.

FIG. 4 is a side view of a button cover with a clasp.

FIG. 5 is an opposite side view of a button cover with a clasp.

FIG. 6 is a back view of a button cover with a clasp.

FIG. 7 is a front view of a button cover with a clasp; and, FIG. 8 is a bottom perspective view of a button cover with a clasp, with the clasp in an open position.

The subject matter shown in broken lines illustrates an environment of use and forms no part of the claimed design.
